ATTORNEY

UNITED STATES PATENT OFFICE.

WILLIAM CHRISTIAN, OF BRIDGEPORT, CONNECTICUT.

MEASURE AND METHOD OF MAKING THE SAME.

Application filed August 19, 1921. Serial No. 493,565.

To all whom it may concern:

Be it known that WILLIAM CHRISTIAN, a citizen of the United States, and resident of Bridgeport, in the county of Fairfield and State of Connecticut, has invented certain new and useful Improvements in Measures and Methods of Making the Same, of which the following is a specification.

The object of this invention is to devise a novel and quite satisfactory measure and to provide an extremely simple method by which the same can be produced.

With the above and other objects in view, the invention will now be fully described and will hereinafter be specifically claimed, it being understood that changes in the sequence of the steps of the method, and in details of construction and arrangement of parts of the finished article can be made so long as within the spirit of the invention and the scope of the claims.

In the accompanying drawing forming a part of this specification,

Figs. 1, 2, 3 and 4 are, respectively, perspective views of an outer tube, an inner tube, a bottom and a rim capable of being assembled to produce the measure of the invention;

Fig. 5 is a perspective view of the measure; and

Fig. 6 is a vertical sectional view thereof.

Referring more especially to Fig. 6 of the drawing, it will be seen that the novel measure consists essentially of a pair of tubes, denoted by 10 and 11, respectively, the tube 10 fitted within the tube 11, a bottom 12 fitted within the lower end of the tube 11 and resting against the lower edge of the tube 10, and a rim 13 fitted upon the upper end of the tube 10 and resting against the upper edge of the tube 11, a preferably metallic band 14 surrounding the lower end of the tube 11 and providing means for receiving nails 15 which pass through the band, through tube 11 and into the bottom of the measure to insure the position of said bottom.

As will be evident from Figs. 1 and 2, the tubes 10 and 11 are desirably of the same length, but the tube 10 is of slightly less diameter than the tube 11 to have a snug, sliding fit therein. These tubes may be of any preferred material. They are desirably constructed of suitable pasteboard, thus in-

suring it that there will be no warping of the body portion of the measure.

As will be evident from Figs. 3 and 4, the thickness of the bottom 12 is approximately equal to the width of the rim 13, and the diameter of said bottom is approximately equal to the internal diameter of said rim. The bottom and rim may likewise be of any preferred material. I desirably construct the bottom of wood and the rim of pasteboard of a thickness greater than that of the tubes, so that in the finished article the rim will project outwardly beyond the tube 11 as it is shown in Fig. 6.

The elements of the measure can be assembled in any preferred manner to produce the article. That is to say, the bottom can be first placed upon a suitable surface, the outer tube can then be slid down over the bottom until its lower edge is in engagement with said surface, the inner tube can then be slid into the outer tube until its lower edge is resting upon the bottom, and the rim can finally be slid down upon the upper end of the inner tube until its lower edge rests against the upper edge of the outer tube; or the rim can be first placed upon a suitable surface, the upper end of the inner tube can be then slid into the rim until in engagement with said surface, the outer tube can then be slid over the inner tube until its upper edge is in engagement with the lower edge of the rim, and the bottom can finally be slid into the lower end of the outer tube to rest against the lower edge of the inner tube; or the tubes can be first assembled and the bottom and rim afterwards placed in their proper positions, as will be obvious. The band 14 and nails 15 are preferably applied after all of the assembling of the other parts is completed. It will be apparent that when the elements of the measure are assembled, the upper edge of the tube 10 and the upper edge of the rim, and the lower edge of the tube 11 and the lower face of the bottom will be flush with each other.

It is to be remarked that during the assembling operations the parts of the measure may be secured in proper fixed relation, preferably with some suitable adhesive substance.

Attention is called to the fact that the present article is of extremely simple con-

struction, and that its method of manufacture can be quickly practiced with the requirement of but a quite limited amount of thought, the measure consisting of but few 5 elements that can be easily assembled.

Having thus fully described the invention, what I claim as new and desire to secure by Letters Patent is:

1. The method of making a measure, which 10 consists in providing an inner and an outer tube of the same length, and a disc bottom and an annular rim the thickness and width, respectively, of which are equal, in fitting said inner tube in said outer tube so that a 15 part of said inner tube projects beyond said outer tube, in fitting said disc bottom in said outer tube and against said inner tube, and in fitting said annular rim over the projecting part of said inner tube and against said 20 outer tube to produce said measure, the fitting of the disc bottom and annular rim being accomplished in such manner that a face of said bottom is flush with an end of said outer tube and an edge of said annular 25 rim is flush with an end of said inner tube.

2. A measure consisting of a pair of telescoping tubes, a disc bottom fitted into the larger tube and against the smaller tube, a band with fastening means fitted about 30 said larger tube and disc bottom, and an annular rim fitted upon the smaller tube and against the larger tube, the upper edge of the annular rim terminating flush with the end of the smaller tube spaced from the disc bottom.

3. A measure consisting of an inner and an outer tube, a part of said inner tube projecting beyond said outer tube and a part of 35 said outer tube projecting beyond said inner tube, a disc bottom fitted into said outer tube and against said inner tube, a face of said bottom lying flush with an end of said outer tube, and an annular rim fitted upon 40 said inner tube and against said outer tube, the upper edge of said annular rim lying 45 flush with an end of said inner tube.

Signed at Bridgeport, in the county of Fairfield, and State of Connecticut, this 12th day of August, A. D., 1921.

WILLIAM CHRISTIAN.
